US00D800313S

(12) **United States Design Patent** (10) **Patent No.:** **US D800,313 S**
Chang (45) **Date of Patent:** **** Oct. 17, 2017**

(54) **HEART RATE SENSOR**

(71) Applicant: **Cal-Comp Electronics & Communications Company Limited**, New Taipei (TW)

(72) Inventor: **Chun-Chieh Chang**, New Taipei (TW)

(73) Assignee: **Cal-Comp Electronics & Communications Company Limited**, New Taipei (TW)

(**) Term: **15 Years**

(21) Appl. No.: **29/569,150**

(22) Filed: **Jun. 24, 2016**

(30) **Foreign Application Priority Data**

May 30, 2016 (TW) 105303053

(51) **LOC (10) Cl.** **24-02**

(52) **U.S. Cl.**

USPC **D24/167**

(58) **Field of Classification Search**

(57) **CLAIM**

The ornamental design for a heart rate sensor, as shown and described.

DESCRIPTION

FIG. 1 is a perspective view of a heart rate sensor showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the heart rate sensor and form no part of the claimed design.

1 Claim, 7 Drawing Sheets
